UNITED STATES PATENT OFFICE.

ERVIN E. WITHEY, OF SYRACUSE, NEW YORK.

HORSE-COLLAR-PAD ATTACHMENT.

SPECIFICATION forming part of Letters Patent No. 375,111, dated December 20, 1887.

Application filed April 14, 1887. Serial No. 234,733. (No model.)

To all whom it may concern:

Be it known that I, ERVIN E. WITHEY, of Syracuse, in the county of Onondaga, in the State of New York, have invented new and useful Improvements in Horse-Collar-Pad Attachments, of which the following, taken in connection with the accompanying drawings, is a full, clear, and exact description.

This invention relates to the class of horse-collar-pad attachments which are secured to the pad and grip the front rim of the collar. Such attachments are usually hook-shaped and formed of spring metal, so as to cause them to embrace closely and nearly completely the front rim of the collar. However, in the use of the collar-pads it is found that the tendency of the pads is to slip rearward only, and consequently the aforesaid close and complete embrasure of the collar-rim by the pad-hook is unnecessary; and I therefore do not limit my invention to either an elastic or a rigid hook.

My invention consists in novel means for securing the said hook to the pad, as herein-after fully described, and specifically set forth in the claims.

In the accompanying drawings, Figure 1 is a front view of a horse-collar with a sweat-pad connected thereto by my improved attachment. Fig. 2 is a view of the rear side of the pad with my improved fastener attached thereto. Fig. 3 is an enlarged detached perspective view of the attaching-hook of the pad with the attaching-strap thereof shown in dotted lines; and Fig. 4 is a transverse section on line y y, Fig. 3.

Similar letters of reference indicate corresponding parts.

A denotes the horse-collar formed with the usual front rim, a; and P represents the sweat-pad, constructed in the usual form, to be interposed between the collar and shoulders of the horse.

C represents my improved pad attachment, which consists of a hook formed in one piece with a flat attaching-shank, c, and carried in a plane at right angles to the flat side of said attaching-shank, and of the requisite size and shape to allow it to be easily slipped over the rim a of the collar A, as shown in Fig. 1

of the drawings. The attaching-shank c, I provide with longitudinal slots t t and an intermediate longitudinal bar, d, as shown in Fig. 3 of the drawings, and I secure said shank to the pad P by means of a strap, e, which I pass through the slots t t at right angles to the shank, so as to bring the central portion of the strap to lie across the intermediate bar, d, on one side of the shank and cause the extremities of the strap to extend in opposite directions from the opposite side of the shank, as illustrated by dotted lines in Figs. 3 and 4 of the drawings, the extremities of the strap being secured to the pad P preferably by means of rivets, as represented in Fig. 2 of the drawings.

I do not, however, confine myself to the use of the strap e, as it is obvious that the slots t t permit of sewing the shank c directly onto the pad P.

Having described my invention, what I claim as new, and desire to secure by Letters Patent, is—

1. In combination with the horse-collar pad, the hook C, formed in one piece with the flat attaching-shank c and curved in a plane at right angles to the flat side of the shank, and said shank provided with the longitudinal slots t t, substantially as described and shown.

2. In combination with the horse-collar pad, the hook C, formed in one piece with the flat attaching-shank c and curved in a plane at right angles to the flat side of the shank, and said shank provided with the longitudinal slots t t and intermediate bar, d, and the strap e, passing transversely through said slot and extending in opposite directions from the shank c and secured to the pad, substantially in the manner described and shown.

In testimony whereof I have hereunto signed my name and affixed my seal, in the presence of two attesting witnesses, at Syracuse, in the county of Onondaga, in the State of New York, this 11th day of April, 1887.

ERVIN E. WITHEY. [L. s.]
